(57) **CLAIM**

The ornamental design for a chair, as shown and described.

DESCRIPTION

FIG. 1 is a front perspective view of the chair of the present invention;

FIG. 2 is a rear perspective view of the chair depicted in FIG. 1;

FIG. 3 is a top, front and left perspective view of the chair depicted in FIG. 1; and,

FIG. 4 is a side perspective view of the chair depicted in FIG. 1.

The broken line showing of the horizontal slats in the chair back is for illustrative purposes only and forms no part of the claimed design.
